FISH LURE

Manuel E. Mecate, 2658 S. Harvard, Los Angeles, Calif.

Filed June 22, 1959, Ser. No. 56,478

Term of patent 14 years

(Cl. D31—4)

Fig. 1 is a top perspective view taken from the rear and one side of a fish lure showing my new design;

Fig. 2 is a side elevational view thereof, the opposite side, not shown, being substantially the same;

Fig. 3 is a bottom plan view thereof;

Fig. 4 is a rear end elevational view thereof; and

Fig. 5 is a front end elevational view thereof.

I claim:

The ornamental design for a fish lure, as shown and described.
